US00D923768S

(12) **United States Design Patent** (10) **Patent No.:** **US D923,768 S**
(45) **Date of Patent:** **** Jun. 29, 2021**

(54) **CIRCUIT KIT FOR A HUMIDIFIER**

(71) Applicant: **Fisher & Paykel Healthcare Limited**,
Auckland (NZ)

(72) Inventors: **Thomas Jacques Fernand Maeckelberghe**, Auckland (NZ);
Gareth James Hobbs, Auckland (NZ);
Matthew Liam Buswell, Auckland (NZ); **Jason Allan Klenner**, Auckland (NZ); **David Leon McCauley**, Auckland (NZ); **Elmo Benson Stoks**, Auckland (NZ); **Samuel Graham Boggs**, Auckland (NZ); **Jonathan Andrew George Lambert**, Auckland (NZ); **James William Stanton**, Auckland (NZ)

(73) Assignee: **Fisher & Paykel Healthcare Limited**,
Auckland (NZ)

(**) Term: **15 Years**

(21) Appl. No.: **29/650,779**

(22) Filed: **Jun. 8, 2018**

Related U.S. Application Data

(57) **CLAIM**

The ornamental design for a circuit kit for a humidifier, as shown and described.

DESCRIPTION

FIG. 1 is a top, rear and side perspective view of a circuit kit for a humidifier showing a tubing assembly embodying our new design;

FIG. 2 is a rear view thereof;

FIG. 3 is a front view thereof;

(Continued)

FIG. 4 is a first side view thereof, the second side being a mirror image thereof;
 FIG. 5 is a top view thereof; and,
 FIG. 6 is a bottom view thereof.
 Broken lines are used to illustrate features of the circuit kit for a humidifier which form no part of the claimed design.

1 Claim, 5 Drawing Sheets

Related U.S. Application Data

division of application No. 29/625,933, filed on Nov. 14, 2017, now Pat. No. Des. 822,817, which is a division of application No. 29/540,276, filed on Sep. 22, 2015, now Pat. No. Des. 807,995.
